UNITED STATES PATENT OFFICE.

ROBERT E. YOLTON, OF BIRMINGHAM, ALABAMA, ASSIGNOR TO KILBY FROG AND SWITCH COMPANY, A CORPORATION OF ALABAMA.

SWITCH-STAND.

1,357,758.

Specification of Letters Patent.

Patented Nov. 2, 1920.

Application filed December 22, 1919. Serial No. 346,503.

To all whom it may concern:

Be it known that I, ROBERT E. YOLTON, a citizen of the United States of America, residing at Birmingham, in the county of Jefferson and State of Alabama, have invented certain new and useful Improvements in Switch-Stands, of which the following is a specification.

My invention relates to switch stands for railways, mine tracks, and the like, which is characteristic by the simplicity of its construction, the absence of gearing, the automatic positive locking of the stand when thrown in either position without the use of latches, and the requirement of but a single pad lock for locking the stand in either operating position.

An important feature of my invention relates to the mechanical elements for transmitting reciprocating motion from the pivoted handle to the connecting rod and in this respect my invention is distinguished by the absence of gears, thereby eliminating lost-motion, and by the provision of means adapted to transmit a differential movement to the switch points relative to the angular travel of the handle to the end that during the movement of the handle through the last 45° of its travel to either side it imparts only a negligible movement to the switch points, thus leaving it practically free of duty as its weighted end approaches position of maximum leverage which insures the handle reaching and remaining in its completely thrown positions and avoids the possibility of a split switch. Split switches generally result from a switch handle not being fully thrown, from a reverse pressure from the switch points opening the latter, or from lost-motion due to excessive wear in the stand. By adapting the handle to throw the switch throughout the upper 90° arc of its 180° travel, I avoid the probability of the switch being only partly thrown.

I have referred above to the feature of lost-motion in the switch stand as occasioning split switches. This is particularly true in the gear operated stands where the switch handle usually has a single narrow bearing which the strains from the heavily weighted handle tend to wear rapidly, thereby giving the handle angular play in its bearings which frequently disconnects the gear and thus leaves the switch points free to open. It is a distinctive feature of my

stand that the handle is supported on either side of its bearing which is elongated to avoid the possibility of angular play or undue lost-motion.

In the present switch stands a lock stand must be provided for the handle at each side and it is an object of my invention to avoid this by using as the transmission element, between the handle and the switch operating crank, a slide which projects at either end beyond its guides and is perforated at each end so that a lock can be applied to the exposed end to prevent the shifting of the member.

A further advantage of my invention is that the crank pin on the handle, utilized to move the shifting transmission element, assumes positions at or slightly beyond dead center when the handle is fully thrown to either side, thus affording a positive lock to prevent displacement of the switch by any external force applied from the switch points or the connecting rod.

A further object of my invention is to so design and arrange the parts that the labor of assembling is reduced to a minimum, thus permitting the initial installation and the substitution of repair parts to be carried out without expert help and at small cost, it being of importance to note that the repair parts can be installed without removing the stand from the track.

In the accompanying drawings, forming a part of this specification, I have illustrated the present standard embodiments of my invention without however intending to be limited to their detail structure.

Referring to these drawings:—

Figure 1 shows a covered switch stand in place with operating connections to the switch points.

Fig. 2 is an enlarged plan view of the operating mechanism with the cover removed as viewed on the section line 2—2 of Fig. 3, the handle being thrown to reverse position from that shown in Fig. 1.

Fig. 3 is a longitudinal partial sectional view taken on the line 3—3 of Fig. 2.

Fig. 4 is a detail view of the transmission slide.

Fig. 5 is a side elevation of Fig. 2.

Fig. 6 is a transverse sectional view taken on the line 6—6 of Fig. 2.

Fig. 7 is a detail view of the crank end of the handle.

105

110

Figs. 8 and 9 are side and end views, respectively, of a modified form of my invention showing an uncovered type of switch stand without a target.

5 Similar reference numerals refer to similar parts throughout the drawings.

I have illustrated my invention as shown in Figs. 1 to 7 as adapted to operate the switch points 1-1 which are connected by 10 a head rod 2 and connecting rod 3 to the crank arm 4 of the stand. This crank arm turns in a boss 5 in the bottom of the casing 6 and has fast on its upper end, which projects above the bottom 6 of the lower 15 half of the casing, a rocker arm 7 which swings horizontally on the bottom 6 as a support and has a slide slot 8 in its free end which projects toward the handle side of the stand. A slide block 9 is adapted to 20 work in the guide 8 and is mounted on a depending pin 10 (see Fig. 4) integral with the transmission slide 11. This slide comprises opposite alining guide arms 12 which rest in slots 13 open overhead and formed 25 in the end walls 14 of the bottom casing. These arms are preferably integral with the central portion of the slide which is vertically elongated and provided with spaced side flanges 15 forming vertical guides for 30 the slide block 16 mounted on the crank pin 17 of the handle 18. The blocks 9 and 16 are alike and interchangeable.

The handle is mounted on a bearing pin 19 which turns in an elongated bearing 20 35 mounted on a bracket 21 integral with the adjacent side wall 22 of the lower casing section. The handle has bearings on either side of the bearing 20, the outer bearing being formed by an extension 23 of the handle 40 in line therewith and perforated to receive the outer end of the pin 19, while the other handle bearing is formed by a crank 30 carrying an annular disk 24 and connected to the handle proper by a lateral web 25 spaced 45 to clear the bearing 20. The headed end of the pin 19 is passed from the inside of the stand outwardly through the disk 24, bearing 20 and handle extension 23, and it will be noted in Fig. 2 that the bearing 20 50 extends inwardly and slightly beyond the inner surface of the side wall 22, this wall, as seen in Fig. 5, being cut away on a curve struck from the pin as a center and extending from the top edge of the web 26 on each 55 side to the top edge of wall 22. The upper casing section 27 is parted from the lower section substantially on the center horizontal plane of the pin 19 and its side wall 28 abutting the side wall 22 is cut away on a 60 half circle concentric with the pin 19, thus forming with the opening in the wall 22, an opening 29 circular except for the interruption by the web 26. The web 25 for the handle turns freely through this opening 65 and the disk 24 on the handle has a slightly

greater diameter than the opening 29 so that it forms an inside turning closure for the same which is sufficiently close to exclude dirt and cinders from the casing without friction on the side walls 22 and 28.

The crank pin 17 is mounted on the crank 30 of the handle and has mounted on it the slide block 16, as appears more clearly in Fig. 3. The slide arms 12 are set below the top level of the end walls 14 and the end 75 walls of the top casing section 27 are provided with tongues 31 which fit down into the slide notches and close the openings above the slide arms 12 and serve additionally to interlock the casing sections.

A target 32 is mounted on a mast 33 which turns in a bearing boss 34 on the top of the casing section 27, the lower end of the mast having a square head 35 adapted to fit detachably into a square socket 36^a in the top 85 of the rocker arm 7 with the center of the mast in line with the vertical axis of the crank 4. A boss 46 on the mast engages the underside of the casing top and serves to hold the mast against upward displacement. 90 The top casing section and the target are thus readily removable without having to disconnect or unbolt any parts except the corner fastening bolts 47 which connect top and bottom casing sections.

The lower casing section is provided at opposite ends with base extensions 36 which are suitably notched for the reception of spikes to anchor the stand to the cross ties. Preferably these base extensions are above 100 the level of the bottom 6 so that the latter will set between the cross ties to better anchor the stand in position. Each slide arm 12 of the transmission slide 11 is provided with a hole 37 so disposed that the hole in each arm will be exposed just beyond the side guide when the handle is moved to shift said arm to its outermost position. This will be clearly seen in Fig. 3, and a pad lock or the equivalent 38 is snapped through the exposed hole 37, thus locking the stand in position in which it is set, as there can be no movement of the switch points when the transmission slide 11 is held. In this connection it is to be noted, 115 by reference to Fig. 5, that the handle at either end of its throw will bring the crank pin 17 in dead center position with pin 19, thus positively locking the stand automatically. Also by reference to the dotted line in Fig. 3, indicating the travel of the crank pin 17, it will be apparent that the crank does practically all of its throwing work during the top 90° arc of its travel. As a result there is but little load on the handle 120 as it approaches horizontal position and thus the weight 39 at the free end of the handle will positively drop it to position in which the stand is automatically locked.

In Figs. 8 and 9 I show a less expensive 130

and simpler type of stand in which the parts are left uncovered and no target is used. Here the crank 4 is mounted in a recessed casting 40 having base extensions 41, each of which carries a pair of vertical lugs 42 which serve as guides for the arms 12 of the transmission slide 11, the slide being held in place by bolts 43 connecting the top ends of each pair of lugs. In this arrangement the bearing 20 for the handle is mounted on a bracket 44 rising from the base casting 40 and the handle has a plain crank arm 45 substituted for the crank 30 and disk 24, as there is no occasion in this design for the latter. The crank pin 17 on the arm 45 carries the slide block 16 which works in the vertical guide in the transmission slide. The pad lock 38 is applied to the outermost hole 37 to lock the slide against the adjacent pair of guide lugs 42.

The operation of both types of switch stands is as follows: Having removed the pad lock 38 the handle is grasped and raised, imparting practically no movement to the switch points until it traverses the upper 90° angle of its movement, the final movement of the handle through the last 45° of its throw likewise imparting but slight movement to the switch points. This small duty during the final part of the throw in either direction enables the weight on the handle to positive carry it at all times to fully thrown position wherein the stand is automatically locked by reason of the crank pin 17 coming to dead center position opposite the bearing pin 19 for the handle. The long bearing 20 and the handle bearings at each end thereof will prevent angular play of the handle, due to wear in the bearings, and there being no gearing in the mechanism there is practically no lost-motion. All wear is practically taken by the slide blocks 16 and 9 which being interchangeable will make displacement charges less. It is to be noted that none of the parts are bolted together except top and bottom of the casing and that all parts can be very readily assembled or taken apart. For instance, the top cover 27 can be unbolted and lifted off, thus freeing the transmission slide 11 to be lifted, after which the pin 19 can be withdrawn and the handle detached. The target shaft will lift off with the top and the rocker arm 8 can then be detached from the crank and lifted out. By reversing the operations, the parts can be assembled and these operations can be performed without disturbing the mounting of the base and without requiring skilled labor. The parts are of such character that they can be made entirely of malleable iron and the castings are of simple character and require a minimum of machine work.

It should be understood that the details of construction can be widely varied without

departing from the novel principles underlying my invention, and I desire to claim the same without limitation to the specific structure shown. 65

Having thus described my invention, what I claim as new and desire to secure by Letters Patent, is:—

1. In a switch stand, a pivoted handle having a weight at one end and a crank pin at the other, a slide block on the crank pin, a horizontally reciprocable slide mounted in the stand and having a vertical guide to receive said slide block, a second slide block attached to the slide, and a switch operating crank having a slide guide for said second block and pivotally mounted to oscillate responsive to the reciprocation of said slide. 75

2. In a switch stand of the character described, a weighted handle having a yoke at its pivot end, a single bearing on the stand embraced at each end by the yoke, a crank at one side of the yoke, and mechanism on the stand operated by the crank for shifting the switch point. 85

3. A switch stand of the character described, comprising a casing having a side opening, a bearing projecting centrally through said opening, a handle journaled in said bearing and having a flange disposed within the switch stand and adapted throughout the lever's travel to close said opening in the casing wall, and mechanism operable by the handle for imparting movement to the switch points. 90

4. A switch stand comprising a casing having an arcuate side opening, a bearing with its center concentric with said opening, a handle having a yoke end embracing the bearing and pivoted thereto, the yoke being movable through said opening and comprising a closure plate to maintain the side wall opening closed, and mechanism operable by the handle to shift the switch point. 105

5. A switch stand comprising a handle, a reciprocable element operable by the handle, a switch point shifting means movable with the reciprocable element, fixed guides for said element, and a key controlled lock transferable to the projected end of said element and adapted by engagement with said guides to lock the projected end of the slide against retraction. 110

6. A switch stand comprising a handle, a reciprocable element operable by the handle, a switch point shifting means movable with the reciprocable element, fixed guides for said element, and transferable means co-acting with said guides and locked to either projected end of the slide to hold it against retraction. 120

7. The combination with a switch stand, of a casing, switch operated mechanism movable therein and comprising an element movable about a fixed vertical axis, a target jour-

- naled in and detachable with the casing top, and vertically detachable means for locking the target with said element for rotation therewith.
5. 8. In a switch stand, a casing comprising a detachable top, a target journaled therein and having a squared end projecting into the casing, handle operated means to shift the switch points comprising a swinging element journaled in the stand and adapted to be moved about a vertical axis and having a squared socket to detachably receive the squared inner end of the target.
9. A switch stand comprising a casing having a detachable top and opposite slots in the end wall of its base section, a reciprocable slide movable through said slots as a guide with one or the other end thereof projecting substantially without the casing,
10. 5. In a switch stand, a handle mechanism for reciprocating the 20 slide, and switch operating mechanism movable by the slide, said slide being vertically detachable from the casing and from the parts operatively connected therewith when the top casing section is removed, substantially as described.
10. In a switch stand, a handle journaled thereto comprising a crank, a reciprocable slide having a vertically elongated guide receiving said crank, guides in which the slide 30 reciprocates, a switch operating crank disposed beneath the slide, and a slide block under the slide for operably and detachably connecting it with said crank.
- In testimony whereof I affix my signature. 35
